[57] CLAIM

The ornamental design for a primitive fire building kit, as shown and described.

DESCRIPTION

FIG. 1 is an exploded front elevational view of the primitive fire building kit showing the individual components of my new design, such components including a bearing block, a dowel drill, a bow, a fire board, and a spark-catching leather piece;

FIG. 2 is an exploded rear elevational view thereof;

FIG. 3 is an exploded right side view thereof;

FIG. 4 is an exploded left side view thereof;

FIG. 5 is an exploded top plan view thereof; and

FIG. 6 is an exploded bottom plan view thereof; and,

FIG. 7 is a top perspective view thereof.

The broken line showing of tinder in FIG. 7 is for illustrative purposes only and forms no part of the claimed design.
